UNITED STATES PATENT OFFICE.

JOSEPH T. BAILEY, OF PHILADELPHIA, PENNSYLVANIA.

DESIGN FOR A BADGE, BROOCH, PIN, BUTTON, BUCKLE, WATCH-CHARM, EMBLEM, INSIGNIA, OR SIMILAR ARTICLE.

44,464.

Specification for Design.

Patented Aug. 12, 1913.

Application filed May 28, 1913. Serial No. 770,518. Term of patent 14 years.

To all whom it may concern:

Be it known that I, JOSEPH T. BAILEY, a citizen of the United States, residing in the city and county of Philadelphia, State of Pennsylvania, have invented a new, original, and ornamental Design for a Badge, Brooch, Pin, Button, Buckle, Watch-Charm, Emblem, Insignia, or Similar Article, of which the following is a specification, reference being had to the accompanying drawing, forming part thereof.

The figure represents, in elevation, a badge showing my new design.

I claim:

The ornamental design for a badge, brooch, pin, button, buckle, watch charm, emblem, insignia or similar article, as shown.

JOSEPH T. BAILEY.
